UNITED STATES PATENT OFFICE.

IRA A. BURNETT, OF CHICAGO, ILLINOIS.

CONTAINER AND HAND BRUSH FOR DISPENSING LIQUID SOAP.

Application filed June 23, 1924. Serial No. 721,681.

To all whom it may concern:

Be it known that I, IRA A. BURNETT, a citizen of the United States, and a resident of Chicago, in the county of Cook and State of Illinois, have invented certain new and useful Improvements in a Container and Hand Brush for Dispensing Liquid Soap, of which the following is a specification.

This invention relates to improvements 10 in a liquid soap dispensing hand brush in combination with a liquid soap container, designed for use generally, as a toilet article, or device for scrubbing and cleansing the hands, but is more particularly intended 15 as an adjunct to the equipment of the toilet or wash-room of dentists, surgeons, and physicians, and it consists in certain peculiarities of the construction, novel arrangement and combination of the various parts 20 or elements thereof as will be hereinafter more fully set forth and specifically claimed.

One of the objects of my present invention is the provision of a liquid soap dispensing hand brush associated and cooperating with a liquid soap container in such a way that the container will act as a reservoir 25 in supplying liquid soap to a suitable receptacle therefor carried by the brush, to the end that a supply of liquid soap will be 30 maintained at all times in the brush ready to be dispensed while the latter is used in the operation of cleaning the hands.

A further object of the invention is the provision of means in the soap container of 35 the brush for ejecting liquid soap therefrom in jets if desired, or to permit the liquid soap to be discharged therefrom more copiously.

Still another object is the provision in the 40 soap discharging means of the brush to admit air to the soap container of the latter at intervals to facilitate discharge therefrom.

Other objects and advantages of the invention will be disclosed in the following description and explanation, which will be 45 more readily understood when read in conjunction with the accompanying drawing, in which an embodiment of which the invention is susceptible is illustrated, it being understood that changes and modifications 50 may be resorted to without a departure from the spirit of the invention so long as they come within the scope of the appended claims forming a part hereof.

In the drawing,—

Figure 1 is a face view of a container and hand brush for dispensing liquid soap, embodying the invention, showing them as being supported in an upright position and at rest side by side.

Fig. 2 is an enlarged longitudinal sectional view through the brush taken on line 2—2 of Fig. 1 looking in the direction of the arrows.

Fig. 3 is a cross-sectional view taken on line 3—3 of Fig. 2 as indicated by the arrows.

Fig. 4 is a plan sectional view taken through the discharge valve casing and plunger therefor of the brush, and

Fig. 5 is a detail showing a modification in the construction of the parts of that end of the brush to which a flexible tube may be detachably secured for supplying liquid soap to the container therefor of the brush.

Like numerals of reference refer to corresponding parts throughout the different views of the drawings.

Referring now more particularly to Figs. 1 to 3 inclusive of the drawings, the reference numeral 7 designates a container for liquid soap which is provided in its upper portion with an opening through which liquid soap can be supplied to the container and which opening is closed by a removable plug or stopper 8 having an upward extension 9 for conveniently removing and replacing the same. The lower end of the container 7 is provided with a vertically depending faucet or cock 10 which is equipped with a shut-off valve 11 of a well known kind. The container 7 may be supported above a wash-basin by means of a suitable bracket secured to the wall and provided with a horizontally disposed band 12 to encircle the container between a pair of spaced beads 13 with which the same may be provided. Extended laterally from the supporting bracket for the container, which bracket is not shown, is an arm 14 provided with an upright pin 15 for engagement with a cap 16 secured to one side of the brush which is designated as a whole by the numeral 17 and is by preference elongated and of about the shape shown in Fig. 1 of the drawing.

The body 18 (see Fig. 3) of the brush is provided with a longitudinally disposed recess 19 which extends from the upper face

of the body 18 to a point near its lower surface as at 20 in Fig. 3, from which point and at its longitudinal middle the body is provided with an opening 21 for the reception 5 of a discharging valve casing of the soap container of the brush, as will be presently explained. As shown, and as will be understood by reference to Figs. 2 and 3, the longitudinal recess 19 is co-extensive 10 with the body 18 and each side wall of the mouth of said recess is provided with an angular rabbet 22 to receive the correspondingly shaped edges of a strap 23 of metal or other suitable material, which can be inserted 15 between the walls of the recess 19 at one end thereof and slid into such position that the ends of the strap 23 will coincide with the ends of the body 18 of the brush. This arrangement affords a detachable but 20 secure closure for the recess as is obvious.

Located in the recess 19 is a liquid soap container designated as a whole by the reference numeral 24, which container is in the form of a tube and is of about the same 25 length as the body 18 of the brush. This container has each of its ends internally screw-threaded and near one of its ends an annular flange 25 through which a plunger rod 26 is extended from one end of the container 24 to a distance between the other end of said container and the discharge 30 valve casing thereof.

The plunger 26 is also extended through 35 the gland cap 27 screwed into one end of the container 24 and employed as a keeper for suitable packing 28 interposed between the flange 25 and the cap 27 for the purpose of preventing leakage. That end of the plunger 26 near the cap 27 is provided with 40 a cavity 28^a with which a pair of spaced openings 29 and 30 communicate, and said end of the plunger is also equipped with a removable head 31 for use in reciprocating the plunger.

45 As shown in Figs. 2 and 3, the plunger 26 is provided near its inner end with a flat or bar-like portion 32 which has a diagonally disposed slot 33 open at its lower end for the insertion of a transversely disposed pin 34 carried by the upper end of a valve stem or plunger 35 which is extended through the discharge valve casing 36 on the lower middle portion of the container 24, which casing is tubular in form and is 50 extended through the opening 21 in the lower surface of the body 18 as well as through an opening 37 in a plate 38 which is provided with depending bristles 39 and secured to the lower face of the body 18 in any suitable way. The plunger 26 is provided 55 near its inner end with a spider-like enlargement 40 which fits snugly in the container 24 yet in such a way as to be readily slid back and forth therein. Extended from 60 the enlargement 40 of the plunger is a pro-

jection 41 around which is located a spring 42 one end of which rests against the enlargement 40 and the other end against an orificed stop member 43 which is provided with grooves 44 on its outer surface for the 70 purpose of affording a seat for a screwdriver which can be used for advancing or retracting the member 43 within the screw-threaded portion of the container 24 in which it is located so as to regulate the 75 tension of the spring 42 which serves to actuate the plunger 26 in one direction.

The plunger 35 or valve stem of the discharge casing 36 of the soap container 24 of the brush is polygonal in cross-section as shown in Fig. 4, and carries on its lower end a valve 45 to close the casing 36 when the plunger rod 26 resumes its normal position after being reciprocated in its container.

Screwed into the end of the container adjacent the stop member 43 is an orificed cap 46 in the opening of which is secured one end of a flexible tube 47 the other end of which is communicatively connected to the discharge end of the faucet or cock 10 on the lower portion of the container 7 or reservoir.

From the foregoing and by reference to the drawing it will be readily understood and clearly seen that by my improvements I have provided a device in which the brush 17 can be supported near the liquid soap container 7 when not in use, and that as it is connected to said container through the 100 instrumentality of the flexible tube 47, liquid soap will pass from the container (assuming that the valve 11 is open) into the container 24 of the brush, and maintained about the same level therein as that of the liquid 105 in the main container, when it is obvious that the brush can be removed from its support and used in cleaning the hands. In the operation of cleaning the hands, soap may be dispensed from the container 24 of the brush by pressing the plunger rod inwardly, which action will force the plunger 35 and valve 45 downwardly, permitting the liquid soap to pass through the passage-ways 110 formed by the cross-sectionally angular 115 plunger or valve stem 35 and the valve casing 36 through and on the bristles and hands.

After inward pressure is removed from the plunger 26, it is manifest the spring 42 will return it as well as the valve 45, to their normal positions. By providing the plunger 26 with the spaced openings 29 and 30 which are connected by a cavity in the plunger as above stated, and by locating one of said openings so that it will normally be exposed to the atmosphere, it is apparent that when the plunger is pushed inwardly, the last named opening will be closed by the cap 27 or packing 28, while the other opening will permit air to escape from the 120 125 130

said cavity into the container 24 and thus facilitate discharge of liquid soap from said container.

It is obvious that the strap 23 or closure 5 for the recess 19 and the body of the brush will be held in position by means of the caps 27 and 46 which engage opposite ends thereof, and that by removing one of said caps, the closure can be slid out of its 10 grooves so as to permit of the removal of the container 24 from the brush if required.

In Fig. 5 is shown a modification in the construction of the means for closing that end of the container 24 in the brush to 15 which a flexible tube may be connected at one of its ends, and its other end to a supply of liquid soap. This modification consists in the employment of a cap 46^a having a threaded opening and provided with an inwardly extended and reduced tubular portion 48 in which is slidably mounted a rod 49 having on its outer end a head 50 and on its other end a valve head 51 to close the inner end of the tubular portion 48. The 20 rod 49 is surrounded by a spring 52 which rests at one of its ends against the head 50 and at its other end against the valve head 51 so as to normally hold said valve head 51 in its closed position. The rod 49 is held 25 against accidental displacement in the member 48 by any suitable means and it will be seen and understood that by screwing the end of a flexible tube such as 47 into the screw-threaded orifice of the cap 46^a a sufficient 30 distance the head 50 and its rod will be advanced in the tube 48, thus unseating the valve head 51 and permit liquid soap to pass into the container 24, which otherwise is of the same construction as shown 35 in Fig. 2 and above described. By this modified arrangement it is manifest that when the tube 47 is removed from the cap 46^a the valve controlling the member 48 will automatically close and thus prevent the 40 escape of liquid from the container.

Having thus fully described my invention,

what I claim as new and desire to secure by Letters Patent is:

1. In a device of the class described, the combination with a bristle carrying body 50 having a longitudinally disposed recess co-extensive therewith and an opening between its ends, of a detachable closure for the mouth of said recess, orificed caps detachably engaging each end of the recess, a 55 plunger rod mounted for reciprocation in said recess and extended through one of said caps, means in said opening between the ends of said recess co-operating with said plunger rod to close said opening, and means 60 connected at one of its ends to the other of said orificed caps and at its other end to a supply of liquid soap.

2. In a device of the class described, the combination with a bristle carrying body 65 having a longitudinally disposed recess co-extensive therewith and an opening between its ends, of a detachable closure for the mouth of said recess, orificed caps detachably engaging each end of the recess and 70 each end of said closure, a plunger rod mounted for reciprocation in said recess and extended through one of said caps, means in said opening co-operating with said plunger rod to close said opening, and means 75 for reciprocating said plunger rod.

3. In a device of the class described, the combination with a bristle carrying body having a longitudinally disposed recess co-extensive therewith and an opening be- 80 tween its ends, of a detachable closure for the mouth of said recess, an orificed cap detachably engaging one end of said recess, a plunger rod mounted for reciprocation in said recess and extended through said cap, 85 means in said opening co-operating with said plunger rod to close said opening, and means communicatively connected at one of its ends to the end of the said recess op- 90 posite that in which said cap is mounted and at its other end to a supply of liquid.

IRA A. BURNETT.
